DEVICE FOR REMOVING YARN RESTS
FROM BOBBINS

Henri-Leopold Boer, Ghent, Belgium, assignor to M. Brouwer & Co., N.V., Hengelo, Netherlands, a limited-liability company of the Netherlands
Filed Jan. 6, 1965, Ser. No. 423,787
4 Claims. (Cl. 28—20)

My invention relates to a device for removing the residual waste yarn from bobbin of the type in which a number of relatively movable claws are arranged in a frame for gripping the bobbin under the residual yarn to be removed, and a pusher is disposed above these claws so as to be movable in a direction perpendicular to the plane of the claws for propelling the bobbin from between the claws with the aid of the pusher.

Such a device is described in the U.S. Patent No. 1,805,452, in which two jaws which are relatively movable in a horizontal plane, and the bobbin to be cleaned clamped between the two jaws. This known device is, however, not suitable for cleaning bobbins with various diameters; in that bobbins with a small diameter are insufficiently gripped, while bobbins with a greater diameter are only engaged at spaced points around their circumference, for example, at the locations where the recess in each claw and the flat portion of the claw merge, these points being moreover not situated at equal distances from the center of the bobbin.

My invention aims to provide a device of the above-mentioned kind in which the aforementioned difficulties are not experienced and with which bobbins of a range of different diameters can be cleaned, the yarn mass being engaged at a sufficient number of points. It is a further object of my invention to provide a very dependable device of simple construction, and in which protection for the operators is also provided.

The object of my invention is accomplished by providing at least three claws connected with pressure members guided so as to be radially movable in a mounting element which is secured to the frame, the pressure members being provided with pins which are perpendicular to the plane of movement and which fit in corresponding cam slots formed in a ring turnable relative to the mounting element and shaped to effect radial movements of the claws upon turning of the ring, and fluid pressure operated means for effecting the turning of the cam ring.

It is a further object of my invention to provide a safety ring which is capable of movement towards the claws and preferably mounted thereabove, the safety ring, when moved, operating a control member by which the upward movement of the pusher is effected.

It is a still further object of my invention to provide a control member operated by a safety ring which can thereby effect a direct connection between a source of fluid under pressure and a membrane or diaphragm for operating a control valve whereby the driving piston for the pusher returns to its uppermost position.

The invention is clarified with reference to the accompanying drawings, showing the device according to the invention.

FIGURE 1 is a vertical sectional view of the device according to the invention;

FIGURE 2 shows a plan view of the claws and their operating mechanism;

FIGURE 3 is a diagram of the pneumatic operating system.

2

As is shown on FIG. 1 the machine consists of a frame 1, which rests on its legs 2. The frame has an erect portion 3 to which a cylinder 4 is secured. In this cylinder 4 there is a reciprocable piston 5 having a piston rod 6 secured thereto and carrying a pusher 7.

Provided in the frame 1 are the claws 8 and their operating mechanism. As is shown in FIGURE 2, there are four of the claws 8 preferably formed of nylon and connected with pressure members 9 which are guided in correspondingly shaped radially directed grooves 10 provided in a stationary mounting ring 11. Each pressure member is provided with an upright pin 12 which fits in a cam slot 13 formed in the underside of a cam ring 14 turnable relative to the stationary ring 11. Each cam slot 13 extends generally in the circumferential direction, but is closer to the outer periphery of ring 14 at one end of the cam slot than at the other end thereof. Turning of the ring 14 will therefore give rise to a radially directed movement of the pressure members 9 and the claws 8 connected therewith. The outer periphery of the ring 14 is connected with a piston rod 15 extending from a piston 16 which is reciprocable in a cylinder 17.

The claws 8 should exert a certain pressure against the circumference of the bobbin 18 to be cleaned and from which the residual yarn 19 is to be removed. For that purpose the bobbin 18 should be brought manually between the claws 8 and thereupon operation of the device is initiated by means of a control member to be described hereinafter.

Upon such initiation of the operation of the device, compressed air is admitted to the cylinder 17 whereby the ring 14 is turned in such a way that the four claws 8 are moved radially inward to grip the bobbin 18 at four locations on its circumference. Only when this bobbin 18 is gripped with a certain force does the operating mechanism supply compressed air to cylinder 4, whereby the piston 5 together with the piston rod 6 and the pusher 7 are moved downwardly to propel the bobbin 18 downwardly from between claws 8 during the last part of the stroke. The residual yarn 19 remains behind on the claws 8 and is stripped from the bobbin.

Provided above the upper plate of the frame is a ring 20, which is secured to a vertical rod 21 slidable in a longitudinal direction in the bearings 22 and 23 carried by the erect portion 3 of the frame. Between a protruding plate 24, secured to the upper end of the rod 21, and the upper side of the bearing 23 is a compression spring 25 which is disposed around the rod 21 and which serves to retain the safety ring 20 in its uppermost position. When one, on introducing a bobbin into the machine, does not withdraw one's hand in time, the same will be pinched between the pusher 7 and the ring 20 whereby the ring 20 is moved downwardly so that a cam 26 secured to the rod 21 actuates a safety valve 27 which controls the pneumatic control system in such manner that the piston 5 is moved upwardly.

The operation of the device is initiated with the aid of a pedal 28 which is secured to the legs 2 and which operates a control valve 29. The way this valve operates and the arrangement of the pneumatic control system are represented in FIG. 3.

Compressed air is fed to the pneumatic control system by way of the connection 30 to a suitable source of compressed air. The compressed air inlet 30 is connected with the port 29a of the valve 29 by way of a pressure regulator 31 beyond which is connected a meter 32, in-

dicating the pressure available for operation of the claw operating cylinder 17. In the rest position of pedal 28, the valve 29 establishes the communications which are represented in full lines on FIG. 3; whereas, when pedal 28 is depressed, valve 29 establishes the communications represented in dotted lines on FIG. 3. In the rest position the compressed air inlet port 29a communicates with the port 17a opening into the space at the left of the piston 16 in cylinder 17, as viewed on FIG. 3. The outlet port 29c of the valve 29, which opens to the atmosphere, is communicated with port 27d in the rest position and port 27d is, in turn, connected to port 17b opening into cylinder 17 to the right of piston 16. Thus, the space at the left of the piston 16 is under pressure when pedal 28 is in the rest position, and the piston is consequently in its extreme right position, so that the ring 14 is turned in such a way that the claws 8 are spaced apart or retracted radially outward as much as possible. The connection between ports 29b and 17a is communicated with a port 31a of a membrane chamber 31 in which the pressure of compressed air supplied to port 17a can act on a membrane 32, to which is fastened the operating rod 33 of the valve 34, so as to hold membrane 32 in a depressed position. This results in the valve 34 remaining in the represented position, in which the port 34a is connected with the port 34b and the port 34c is connected with the port 34d. Since the port 34a is connected with the pressure piping by way of the regulator 35, and the port 34b is connected with the port 4a at the lower end of cylinder 4, the space under the piston 5 in the cylinder 4 is under pressure; and the space over the piston 5 communicates with the atmosphere by way of the port 4b connected to port 34d which communicates with the port 34c opening to the atmosphere. The piston 5 will consequently be in its uppermost position.

The device operates as follows:

On pressing the pedal 28 the communications between the ports of the valve 29 are established as is indicated by dotted lines. This means that the space at the right of the piston 16 is put under pressure by way of the connection from port 17b to port 29d and the valve connections from port 29d to port 29f, while the space at the left of the piston 16 communicates with the atmosphere by way of the connection from port 17a to port 29b, and, within the valve, between ports 29b-29e. The piston 16 moves to the left whereby the claws close or move radially inward. During such movement there is maintained a certain pressure at the left of the piston 16 and acting upon the membrane 32, as the air cannot escape fast through the pipes and the valve 29. As a result the valve 34 is not immediately switched.

When the piston 16 no longer moves because the claws 8 press against the bobbin, the pressure at the left of the piston 16, and which acts on the membrane 32, drops. When this pressure has fallen off below a definite value, the valve 34 switches whereby this valve establishes the communications which are indicated in dotted lines on FIG. 3. Compressed air at a pressure indicated by a pressure gauge 36 is admitted to the valve 34 by way of the regulator 35, and passes through valve 34 from port 34e to port 34d to act in the space within cylinder 4 above piston 5, while the space under the piston communicates with the atmosphere by way of the connection through valve 34 between ports 34b-34f. The piston 5 moves downwardly and, by way of the piston rod 6 and the pusher 7, moves the bobbin downwardly from between the claws. After the pedal 28 is released, the control system returns to its rest position.

The safety valve 27 to be operated by the cam 26 on rod 21 is interposed in a conduit connecting the compressed air inlet 30 with the line extending from port 17a to port 31a. Actuation of valve 27 results in that there is a pressure again in the space over the membrane 32 whereby this membrane is depressed, and the valve 34 establishes the communication as represented in full lines

in FIG. 3, whereby the piston 5 moves immediately upwardly.

As is obvious from the description the invention provides a simple dependable apparatus for removing residual yarn from bobbins, the said apparatus being capable of dealing with an extensive range of diameters of bobbins. Due to the less complicated construction the device is very dependable while the simple operation allows for the removal of residual yarn from the bobbins at a rate which is considerably faster as compared with the old method.

What I claim is:

1. A device for stripping residual yarn from bobbins, comprising a frame, a mounting ring fixed on said frame, 15 at least three pressure members guided in said mounting ring for radial movement relative thereto, said pressure members each carrying a claw for radial movement therewith in a plane common to the plane of movement of the claws carried by the other pressure members so 20 that the claws can grip a bobbin under the residual yarn to be removed therefrom, each of said pressure members having a pin projecting therefrom perpendicular to said plane of movement, a cam ring turnable on said mounting ring and having a cam slot therein for each of 25 said pressure members which receives said pin projecting from the related pressure member, each cam slot extending generally circumferentially in said cam ring and having its opposite ends at different distances from the outer periphery of the cam ring so that turning of the latter causes radial movements of said claws to selectively grip and release a bobbin positioned amid said claws, fluid-pressure operated means for turning said cam ring, and a pusher mounted on said frame above said claws and being movable perpendicular to said plane of movement of the claws so as to slidably displace a bobbin from between said claws while the latter grip the bobbin for stripping the residual yarn therefrom.

2. A device according to claim 1; further comprising 40 a safety ring mounted above said claws and being movable toward the latter, and control means operated in response to movement of said safety ring toward the claws to effect movement of said pusher in the direction away from said claws.

3. A device according to claim 1; wherein said fluid 45 pressure operated means includes a first cylinder having a piston reciprocable therein and connected with said cam ring to turn the latter, a source of fluid under pressure, first valve means interposed between said source and both ends of said cylinder to normally supply fluid under pressure to one end of said cylinder and to exhaust the other end of said cylinder for moving said piston in the direction displacing said claws radially outward, an operating member connected with said first valve means and being actuatable to cause said first valve means to exhaust 50 said one end of the first cylinder and to supply fluid under pressure to said other end of the latter, whereby said claws are displaced radially inward to grip a bobbin therebetween, a second cylinder having a piston reciprocable therein connected with said pusher to move the latter perpendicular to said plane of movement of the claws, second valve means interposed between said source and both ends of said second cylinder and having an actuating diaphragm, and conduit means extending from said one end of said first cylinder to apply the pressure of 55 fluid acting therein against said actuating diaphragm of said second valve means, said second valve means being operative when the pressure of fluid acting against said diaphragm exceeds a predetermined value to supply fluid under pressure to said second cylinder in the direction 60 for moving said pusher away from said claws and to reverse the direction in which fluid is supplied to said second cylinder for moving said pusher toward said claws when the pressure of fluid in said one end of the first cylinder and acting against said diaphragm falls below 65 said predetermined value.

4. A device according to claim 3; further comprising a safety ring mounted above said claws and being movable toward the latter, and means responsive to movement of said safety ring toward said claws to establish communication between said source of fluid under pressure and said membrane, whereby said second valve means causes said second cylinder to move said pusher away from said claws.
